FIG. 5.

Patrick O. Perry, Inventor
Patrick O. Perry
Atty.

UNITED STATES PATENT OFFICE

2,392,337

WINDOW BLIND FIXTURE

Patrick O. Perry, Halifax, Nova Scotia, Canada

Application April 10, 1944, Serial No. 530,436

1 Claim. (Cl. 248—267)

This invention relates to improvements in window blind fixtures its primary object being to provide a fixture that may be easily installed.

A further object is to provide a fixture that may be installed with a minimum of damage to window frames.

A still further object is to provide a fixture that will be efficient and durable and inexpensive to manufacture.

With these and other objects in view that may appear while the description proceeds the invention consists in the novel construction, and arrangement of parts as hereinafter more specifically set forth, claimed and shown in the accompanying drawing forming part of this specification and in which:

Fig. 1 is a perspective view of the end of the fixture attached to the rotating end of the blind.

Fig. 2 is a similar view of the end of the fixture attached to the fixed or spring end of the blind.

Figs. 3 and 4 are modified views of the fixture combining the use of a detachable screw.

Fig. 5 is another modified view of the fixture.

Fig. 6 is a view showing the method of forming the base of the fixture as shown in the modified view in Fig. 5.

Referring more in detail to the drawing in which similar reference characters designate corresponding parts throughout the several views it will be seen that the invention comprises a pair of bases 10, 10a, having side pieces 11, 11a, angularly disposed thereto.

The side pieces 11, 11a, are identical with the exception that the end of side 11, has a hole 12, to receive the rotating end of the blind roller while side 11a, has a slot 13, to hold the fixed or spring end of the blind roller in position. Having this in mind, the base 10, is the only one that need be hereinafter referred to for the purpose of this invention.

A threaded screw 14, is secured to the base 10, so that the fixture may be attached to the window frame by turning by hand, and the head of the screw 14, is provided with a conventional slot

15, so that if desired a screw-driver may be used to attach the fixture to the window frame.

In the modified form of the fixture as shown in Figs. 3 and 4, a groove 16, is cut in the base 10, 10a, are shoulder retaining means associated with groove 16, 17, is a threaded screw having a square cut shoulder 18, which engages in the groove 16, enabling the fixture to be attached to the window frame by turning by hand. The head 10 of this screw 17, also is provided with a conventional slot so that a screw driver may be employed to attach the fixture to the window frame if desired.

Fig. 5 shows a further modification of the fixture in which the threaded portion 19, is an integral part of the base 10, permitting the fixture to be attached to the window frame simply by hand turning. The method of forming this threaded portion 19, is clearly shown in Fig. 6, in which the center part 20, of the base 10, is stamped out by means of dies 21, 22 and becomes the threaded portion 19.

It is believed that the construction and advantages of the device may be apparent from the foregoing paragraphs taken in conjunction with the accompanying drawing without further detailed description.

While the preferred embodiment of the invention has been disclosed it is understood that minor changes in the combination and arrangement of cooperating parts may be resorted to within the scope of what is claimed without departing from the spirit of the invention.

I claim:

35 A shade fixture comprising a base having an angularly disposed portion forming a shade supporting arm, said base having a slot therein opening through an edge thereof, a screw shank having a head and a square shoulder beneath said head of corresponding width to the slot of said base and adapted to engage in the slot, and lugs projecting from the edges of the slot for engaging the shoulder of said screw shank to retain the same in said slot.
